ATTORNEY

UNITED STATES PATENT OFFICE.

FRANZ POLLITZER, OF GROSSHESSELOHE, NEAR MUNICH, GERMANY.

PROCESS FOR TRANSFERRING HEAT FROM GASES TO OTHER GASES.

Application filed October 23, 1926, Serial No. 143,674, and in Germany July 31, 1925.

For the purpose of transferring heat from gases to other gases one of the following two ways is generally in use: either the gases are conveyed in a counter-current through 5 tubes, the heat being transferred by the walls of the tubes from one gas to the other one; or the heat is transferred by the aid of solid materials, over which the gases are alternately conducted, separated from each other, 10 and which absorb the heat from the hot gases and transfer it to the cold ones. The first mentioned manner of operating requires large surfaces for transferring the heat and consequently voluminous and expensive ex- 15 changers. In many cases, for instance when air or other gases with a high relative humidity are to be cooled, the tubes will be obstructed by ice which cannot be removed without an interruption of the operation. 20 The process above mentioned in the second place may be carried out with an apparatus relatively simple and less expensive, but in this case a device for interchanging the flow of gases and a rather complicated control 25 are required.

The invention consists in a process for transferring heat from gases to other gases by which the above mentioned disadvantages are avoided. According to the invention the 30 transmission is effected by the aid of a liquid. By a circulation process this liquid is successively brought into direct communication with the gases to be treated. The utilization of liquid as an auxiliary body, which is 35 driven through the cycle by means of a pump, has the advantage, that it thereby becomes possible to work in an absolutely continuous manner; on the other hand by drizzling a liquid over a gas, the transfer of heat 40 is effected in a very advantageous manner. A further advantage of this manner of operating is to be seen in the fact that it may be carried out by the aid of a simple apparatus of relatively small dimensions.

15 The carrying out of the new process will now be described by way of example by reference to the accompanying drawings.

Fig. 1 shows diagrammatically an arrangement for carrying out the invention 20 wherein the heat exchange is from a compressed gas to an expanded gas, while Fig. 2 shows diagrammatically a modification of this arrangement.

Figure 1 illustrates the case of the ex- 25 change of heat from a compressed gas to an

expanded gas, for instance for the purpose of liquefaction, and assuming as the object of the liquefaction a refrigeration output at the temperature of the methane under atmospheric pressure. We choose as an example the liquefaction of ethylene, using toluene as an auxiliary liquid. The compressed ethylene enters the first column A at the temperature of cooling water, leaves the column at its higher end *b* and is expanded 60 to the pressure of one atmosphere by the regulating valve V. The gas thus cooled by expansion enters the second column B at *c* in which it will ascend and cool the descending liquid. Now, inasmuch as this cooling is 65 transferred to the liquid trickling down in tower B, and since the latter (i. e. the liquid) thus pre-cooled yields its cold in tower A to the gas flowing to valve V, it will be seen 70 that the temperature fall occasioned by expansion leads to lower temperatures in the rear of the valve V than previously. This, in turn, leads to greater cooling of the liquid in B, and thus to further pre-cooling of the 75 gas in A; the temperature on both sides of valve V decreases steadily until, when a state 80 of stability is attained, liquefaction of the gas is produced in the rear of V. The cooled toluene runs from the container *e* to a pump P, where it will be brought to the pressure of 85 the compressed ethylene. Then it is introduced into the column A at *f* in which it cools the compressed ethylene. When leaving the column A at the lower end by *g*, it has approximately the initial temperature 90 of the ethylene entering at *a*. Now the gas is brought to the upper end of the column B (at *h*) by the aid of an expansion valve D. The described apparatus has a mode of 95 operating similar to that of the well-known counter-current apparatus provided with two or more tubes. When the upper column has reached a low temperature the non-liquefied part of the ethylene enters the apparatus at 100 *c* at the temperature of its boiling-point. The quantity of the circulating liquid must be regulated in such a manner that it is sufficient to heat the gas passing through the column B up to ordinary temperature. In 105 the column A the liquid may then absorb the same quantity of heat from the compressed gas passing the column.

The auxiliary liquid must consist of a material which meets the following requirements. On the one hand it is necessary that 110

it will not become too viscous at the lowest temperature and on the other hand it must have such a vapour-tension at the highest temperature that the escape of material will not cause a considerable loss. The evaporated quantities are to be continuously replaced by addition of further liquid from a container E. It may also be advisable to recover the vapour passing off together with the gas, for instance by absorption or dissolution.

In cases where a liquid of the desired qualities is not at disposal, two or more liquids should be used for the different ranges of temperature and two or more devices of the described kind should be arranged one after the other. It is also possible to combine the described apparatus with a counter-current of another kind of construction for different ranges of temperatures.

In order to obtain a complete heat-exchange of liquid and gas, the heat capacity must be regulated in such a manner that it will be approximately equal at all temperatures. If the specific heat of the liquid decreases at lower temperatures in a quicker manner than that of the gas, as it may be often the case, this diminution may be equalized by increasing the quantity of circulating liquid in the cooler parts of the column. This mode of operating is illustrated by Fig. 2. The liquid is partially passed off at g_1 and conveyed through the valve D_1 to the column B at h_1 . The remaining liquid passes through the whole length of the two columns in the same manner as shown in Figure 1. In cases where more than two gases are to be treated, it is necessary to provide for a corresponding number of columns, so that a special column is available for each gas.

Having now particularly described and ascertained the nature of my said invention,

what I claim and desire to secure by Letters Patent of the United States is:

1. A process for transferring heat from gases to other gases which comprises causing a compressed gas to ascend through a descending shower of a cool liquid in a cooling chamber, expanding said gases thereby further cooling the same and causing said gases to ascend through a descending shower of a warm liquid in a second chamber.

2. A process for transferring heat from gases to other gases which comprises causing a compressed gas to ascend through a descending shower of a cool liquid in a cooling chamber, expanding said gases thereby further cooling the same, causing said gases to ascend through a descending shower of a warm liquid in a second chamber, said liquid thus cooled by heat exchange with the expanded gases being forced into the first mentioned chamber, descending therein in heat exchange with said compressed gas before expansion and returning said liquid for use in said second chamber.

3. A process for transferring heat from gases to other gases which comprises causing a compressed gas to ascend through a descending shower of a cool liquid in a cooling chamber, expanding said gases thereby further cooling the same, causing said gases to ascend through a plurality of vertically spaced descending showers of a warm liquid in a second chamber, said liquid thus cooled by heat exchange with the expanded gases being forced into the first mentioned chamber, descending therein in heat exchange with said compressed gas before expansion and successfully withdrawing said liquid at vertical intervals from said first chamber and returning the same to corresponding showers in said second chamber.

FRANZ POLLITZER.
